Application August 28, 1934, Serial No. 741,772

4 Claims. (Cl. 126—163)

My invention relates to fuel-supporting structure for combustion apparatus and it has for an object to provide for improved air admission with variable conditions of the fuel bed.

5 Heretofore, the fuel-burning grate of combustion apparatus has frequently consisted of fuel-supporting members with holes extending therethrough or therebetween for the admission of air into the fuel bed for supporting combustion. The 10 draft, in natural draft furnaces, or the air pressure, in forced draft apparatus, causes flow of air through such holes and through the fuel bed. Usually, the holes have been either straight or slightly tapered, the resistance to flow of air increasing as the holes are decreased in size. In 15 any fuel bed, it is well known that the resistance to flow, or drop in pressure through the fuel bed is not uniform throughout its area and heretofore the straight or tapered holes or passages have offered but little change in pressure drop 20 with increased flow, in consequence of which the sections of the fuel bed, which offer decreased resistance to flow, either because of the character or thinness of that section of the fuel bed, 25 would be supplied with an excess amount of air, thereby increasing the combustion rate in such sections and resulting in burning out of the fuel bed on such sections relatively faster than on other sections.

30 In order to overcome the aforementioned irregularity in combustion, grates with pin holes have been used. However, the holes are usually so small that high resistance to air flow therethrough results, thereby making the pressure drop through the holes the predominating resistance. In other words, the holes being of small area, the pressure drop through the grate is large compared to that of the fuel bed and variation in character or thickness of the fuel bed have 35 but little effect on air flow. With this type of grate, in order to secure necessary air flow higher differential pressures are required, making it essential to provide higher stacks, or, in the case of forced draft, larger blowers and increased 40 power for driving the latter.

45 In accordance with my invention, I provide a fuel-supporting structure wherein the air passages are constructed and arranged to give a variable resistance to air flow therethrough without the necessity of providing high differential pressures. This and other advantages are obtained by having the elements forming the fuel-supporting surfaces provided with means of securing a series of orifices in each air passage 50 with chambers between adjacent orifices, the air

passing through the orifices at high velocities and having the velocity energy largely transformed into static pressure in the chambers following the orifices.

5 In order that air may be sufficient for supporting combustion, there must be enough pressure difference between the space underneath the grate and the space above the fuel bed to overcome resistance to air flow through the air passages of the grate and through the fuel bed. 10 Ordinarily, the grate air passages offer little resistance, with the result that irregularities in fuel bed resistance may cause undesired irregularities in air flow. For example, excess flow may occur in a region of small fuel bed resistance, thereby 15 increasing the combustion rate at such region and bringing about lessened pressure difference and consequent lessened flow through regions having greater fuel bed resistance. As hereinbefore already pointed out, an attempt to meet this objection has been made by providing very small air passages, but such small air passages are undesirable because of the consequent high pressure required to secure necessary air flow. It is well known that the flow through an orifice is a 20 function of the square root of the pressure difference across the orifice. Accordingly, instead of accomplishing increased resistance to air flow through a grate provided with relatively small 25 passages, I provide a labyrinthine arrangement 30 consisting of orifices with chambers between adjacent orifices. In other words, I provide for abrupt changes in area of flow from a chamber to an orifice and vice versa in each passage, the effect of the abrupt flow area being to decrease 35 the quantity of air flowing compared to a plain passage. The air has maximum velocities through the orifices, but, due to abrupt changes in area, large losses occur incident to changes of velocity energy into pressure energy and 40 vice versa, and also definite energy losses due to conversions, with the result that, should there be a decrease in resistance at the discharge end of the passage, such decrease is compensated 45 for by the increased effective resistance of the passage with very little increase in flow therethrough.

45 This arrangement of orifices with chambers between adjacent orifices in the air passage causes the flow to increase at a lesser rate in 50 case of diminishing fuel bed resistance than with other types of air admitting grates. In other words, in accordance with my invention, grate resistance to air flow due to the losses from the 55 changes in air velocity in passing through the

alternate orifices and chambers is increased thus producing a choking effect against excessive air flow without substantially increasing the air pressure required to secure the normal flow. This choking effect increases the grate resistance to air flow and tends to counteract the lower pressure drop through sections of the fuel bed of low resistance. This arrangement of air passage is more effective than the ordinary grate in equalizing the rate of air flow through the various sections of high and low resistance in the fuel bed, thus securing more uniform combustion over the entire fuel bed area.

Accordingly, it is a more specific object of my invention to provide the air admitting passages of grate members each with a series of orifices and chambers between adjacent orifices, this arrangement functioning to prevent substantial irregularities of combustion with irregularities in fuel bed resistance.

These and other objects are effected by my invention, as will be apparent from the following description and claims taken in connection with the accompanying drawings, forming a part 25 of this application, in which:

Fig. 1 is a transverse sectional view of a single retort stoker having my improvement applied thereto;

Fig. 2 is a sectional view taken along the line 30 II-II of Fig. 1;

Fig. 3 is a fragmentary view of a chain grate having my improvement applied thereto.

Fig. 4 is a fragmentary detail view showing my improvement applied to tuyère plates of an underfeed stoker;

Fig. 5 is a bottom plan view of one of the tuyère plates shown in Fig. 4;

Figs. 6 and 7 show a further embodiment of the improvement applied to tuyère plates;

Figs. 8 and 9 are detail views of stoker grate bar elements embodying a second form of my invention;

Figs. 10 and 11 are sections taken along the lines X-X and XI-XI, respectively, of Fig. 9;

Fig. 12 is a view similar to Fig. 8 and showing a modified mode of securing variation in air flow;

Figs. 13, 14, and 15 are sectional views taken along the lines XIII-XIII, XIV-XIV, and XV-XV, respectively, of Fig. 12;

Fig. 16 is a fragmentary view of a tuyère plate incorporating the second form of my invention;

Figs. 17, 18, and 19 are detail views of side-wall tuyères incorporating my improvements, Fig. 19 being a sectional view taken along the lines XIX-XIX of Fig. 18.

Referring now to the drawings more in detail, in Fig. 1, I show a structure including a retort, at 10, having sets of grate bars 11 extending laterally therefrom, this being a well-known type of single retort underfeed stoker and which necessitates no further description in detail.

As is well known, fuel is supplied to the retort and flows laterally over either side thereof onto the grate bars 11, the fuel advancing downwardly on the grate bars at either side of the retort and being consumed.

Air for the combustion of fuel flows through the grates and fuel bed due to the pressure difference existing between the space 12 below the structure and the space 13 in the combustion chamber.

In order that a choking effect may be secured in the air passages between adjacent grate bars 11, in Figs. 1 and 2, I show the bars provided with ribs 14, 15, 16, and 17 cooperating to provide

first, second, third, and fourth stage orifices 18, 19, 20, and 21 with chambers 22, 23, and 24 between adjacent orifices 18 and 19, 19 and 20, and 20 and 21, respectively, it being understood that, any suitable number of orifices arranged in series 5 may be provided. In these figures, as well as the others hereinafter described, each air passage consists of one or more chambers and orifices leading to and from each chamber. This arrangement provides for abrupt changes in flow 10 area where the orifices and chambers connect. The abrupt change in area is productive of inefficient conversion of velocity energy into pressure energy and vice versa and the effect thereof is to reduce the quantity of air discharged 15 compared to a plain passage. With passages of this type, if the fuel bed is uneven, or if the resistance thereof varies, the differences in air flow that would otherwise be induced by such variation tends to be equalized by the effect of the 20 passages. While a decrease in resistance at the discharge end of a passage tends to increase the flow of air through the passage, because of the abrupt area changes and consequent inefficient energy conversions, very little increase in flow is 25 required to compensate for the diminished resistance. Accordingly, with my improved grate surface, the tendency of air to flow through thin places, or places of lesser resistance, with an undesirable loss in air and impaired combustion 30 efficiency is overcome. With my arrangement, due to the inherent choking effect of each passage, variations in fuel bed resistance are largely compensated for by the operating effect of the 35 passages in consequence of which variations in fuel bed resistance are not accompanied by proportionate variations in air flow, to the regions of the fuel bed inconsistent with the actual requirements of the latter.

In Fig. 3, showing my improvement applied to 40 a chain grate, the links 25 have ribs 26 at their sides which cooperate to define passages of varying area in the direction of flow, as in Fig. 1. Also the ends of the links have ribs 27 serving the same purpose.

In Figs. 4 and 5, I show my invention as applied to a series of tuyère plates 29 of an underfeed stoker, these plates being arranged in stacked relation and providing for the admission of air horizontally therebetween. The air passing from 50 a region, at 12, at higher pressure to the combustion space, at 13, at lower pressure. The horizontal passages between adjacent tuyère plates are provided with a series of orifices and chambers to accomplish the effect already pointed out. 55 To this end, referring to Fig. 5, I show the bottom side of the tuyère plate provided with a series of ribs 30, 31, 32, and 33 which are notched as indicated at 34, 35, 36, and 37, respectively, the notches being sufficient in number and size in 60 each rib row to secure the desired orifice area. With the tuyère plates in position, as shown in Fig. 4, the rib rows 30, 31, 32, and 33 rest on the flat top surface of the tuyère plate immediately 65 below, and the notches 34, 35, 36, and 37 are effective as first, second, third, and fourth stage orifices to secure the aforementioned choking effect.

Instead of having notched ribs provided on the under surfaces of the tuyère plates, as shown 70 in Figs. 4 and 5, each of such ribs may be made continuous and spaced from the top surface of the tuyère plate immediately below, the spacing of the respective ribs being such as to secure the desired orifice area. For example, in Figs. 6 and 75

7, I show ribs 38, 39, 40, and 41 disposed in the direction of air flow and arranged successively closer to the top surface of the tuyère plate immediately below so as to afford the desired first, 5 second, third, and fourth stage orifice areas, the tuyère plates being supported in properly spaced relation by the projections 41a.

To compensate for varying fuel bed resistance, the choking effect of the air passages may be 10 varied along the fuel-supporting surface, this feature being illustrated in Figs. 8 to 15, inclusive.

In Figs. 8 to 11, inclusive, I show grate bars of the type illustrated in Fig. 1 and having lateral ribs 42, defining orifices, or air passages of 15 varying area in the direction of flow, as already pointed out in connection with Fig. 1; however, instead of having orifices or restricted passage portions of uniform widths from end to end of the grate bars, as in Fig. 1, such portions, in 20 Figs. 8 to 11, inclusive, vary in width so as to compensate for variation in fuel bed resistance, the flow resistance of the passages being less where the resistance of the fuel bed is a maximum and vice versa. To this end, it will be seen 25 that the ribs 42 are not continuous but are divided into a plurality of sections considered lengthwise of the grate bars, the sections being shown at 42a, 42b, and 42c, adjacent sections, preferably, being separated by mating ribs 43 30 and 44.

The ribs 42a define orifices 45 of maximum width, the ribs 42b define orifices 46 of intermediate width, and the ribs 42c define orifices 47 of minimum width, the orifice width depending 35 upon the fuel bed resistance.

Obviously, with the type of stoker shown in Fig. 1, the fuel bed will be of maximum depth, and, therefore, resistance, at the forward ends of the bars, this maximum fuel bed resistance 40 being at the sections 42a where the width of the orifices 45 is at a maximum. The fuel bed depth diminishes along the bars, being of intermediate depth at the section 42b where the orifices 46 are of intermediate width, and being of 45 minimum depth at the discharge ends of the bars, i. e., at the rib section 42c, which define the orifices 47 of minimum width.

With this modification of the rib structure on the grate bars, it will be apparent that variation 50 in the fuel bed resistance is compensated for by variation in passage resistance so that the tendency of air to flow excessively through the grate where the fuel bed is thin, is minimized.

Instead of varying the orifice width from end 55 to end on the grate bars, as in Figs. 8 to 11, inclusive, the same result may be secured by varying the number of orifices at different sections along the bars. To this end, in Figs. 12 to 15, inclusive, I show grate bars having rib sections 60 48a, 48b, and 48c defining orifices 49a, 49b, and 49c, respectively, the sections 48a being separated from the sections 48b by transverse mating ribs 50 and sections 48b being separated from the sections 48c by ribs 51. As the orifices 49a, 49b, 65 and 49c are of uniform width, variation in resistance is secured by varying the number of orifices, the number of orifices being at a maximum where the fuel bed is thinnest and at a minimum where the fuel bed is thickest.

70 With an underfeed stoker, it is obvious that the fuel bed immediately above the tips or noses of the tuyère plates is at a minimum, for, if one views a tuyère row in the plane of the tuyères, it will appear as a convex surface. Accordingly, in Fig. 16, I show tuyère plates similar to that

shown in Figs. 6 and 7, having lower ribs divided into sections 53a and 53b adjacent sections being separated by ribs 54, and the sections 53b being at the noses or tips of the tuyère plates. The rib sections 53a and 53b extend downwardly from the lower sides of the tuyère plates to cooperate with the upper horizontal surface of the next lowermost plate, as in Fig. 6. The rib sections 53a define orifices with respect to the upper horizontal surface of the next lowermost plate which 10 are wider than the orifices defined by the rib sections 53b at the tip or nose of the tuyère plate, whereby less resistance to flow is afforded by the rib sections 53a than the sections 53b, the fuel bed being, obviously, thicker above the lateral 15 sections 53a than above the nose or tip rib sections 53b. Also, it will be apparent that the ribs constitute spacing supports for the tuyère plates when the latter are disposed in assembled 20 stack relation.

The general principles of my invention may also be applied to other types of structures used with combustion apparatus. In Fig. 17, I show a sidewall tuyère 55 incorporating my invention, each of the air passages 56 having one or more 25 chambers 57 so that the portions of the passages to either side of the chambers serve as orifices. Here again, each air passage has varying areas in the direction of flow so as to secure 30 the effect already pointed out.

In Fig. 18, I show a modified form of sidewall tuyères, where, instead of having an extensive or large casting such as indicated at 55 in Fig. 17, the tuyère device includes a plurality of vertical 35 sections or bars 58 disposed side by side. The sections have mating ribs 59 defining orifices 60, the orifices being separated by chambers 61. In this form, it will be apparent that each of the air passages has varying area in the direction of flow for 40 the purpose already pointed out.

From the foregoing, it will be apparent that I have provided a fuel-supporting or fuel-contacting surface through which air is supplied and wherein the air passages are so formed that variation in fuel bed resistance does not cause a large 45 difference in flow of air through the different passages, that is, the passages prevent excessive flow of air to portions of the fuel bed where the fuel bed resistance is a minimum. While passages of uniform character for the entire bed are effective 50 for this purpose, I may modify the passages to suit the varying character of the fuel bed. For example, if the fuel bed is normally thicker at certain regions than in others, then the orifices 55 may be arranged to afford less resistance to flow of air where the fuel bed is thickest and greatest resistance where the fuel bed is thinnest, the effect of the arrangement being that the variation in the air passages compensates for variation in fuel bed resistance. Variation in the air 60 passages to compensate for variation in fuel bed resistance may be secured by either varying the number of orifices at different sections of the fuel-supporting surface, or by varying the sizes of the orifices at different sections, or by both.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In combustion apparatus, a grate including a plurality of bars arranged side-by-side to provide vertical passages between adjacent bars for supplying air from the space below the grate to the space thereabove, said bars having spaced lateral ribs extending longitudinally thereof, the ribs providing orifices extending longitudinally of the bars and the spaces between adjacent ribs providing enlarged chambers extending longitudinally of the bars, each passage including a plurality of chambers and orifices with the chambers arranged between successive orifices.
2. In combustion apparatus, a grate including a plurality of bars arranged side-by-side to provide vertical passages between adjacent bars for supplying air from the space below the grate to the space thereabove, said bars having spaced lateral ribs at each side and extending longitudinally thereof, similar and opposed ribs on adjacent bars forming a plurality of orifices separated by enlarged chambers formed by the spaces between adjacent ribs, whereby each passage includes a plurality of orifices with the chambers arranged between successive orifices.

3. In combustion apparatus, a grate providing a fuel supporting surface having air admission openings and means cooperating with the grate to provide a multiplicity of chambers arranged in series in the direction of air flow, said means and the grate providing a plurality of spaced walls extending transversely of the direction of air flow and defining and separating the chambers and said walls having restricted openings, including said air admission openings, providing a plurality of orifices, whereby the air flow passage to the fuel supporting surface is comprised by a plurality of orifices and a plurality of chambers with the chambers arranged between successive orifices in the direction of air flow.

4. In combustion apparatus, a grate element having three or more spaced ribs extending laterally therefrom and adapted, when the element is assembled with respect to an adjacent element, to provide three or more spaced orifices in the passage between the elements, the spaces between adjacent ribs providing expansion chambers between successive orifices.

EARLL R. STONE.
